INVENTOR:
MORRIS WILLIAM TRAVERS,

By his Attorneys,
Baldwin & White

UNITED STATES PATENT OFFICE

MORRIS WILLIAM TRAVERS, OF CLIFTON, BRISTOL, ENGLAND, ASSIGNOR TO REGENERATIVE COAL GASIFICATION SYSTEM, LIMITED, OF LONDON, ENGLAND

APPARATUS FOR THE MANUFACTURE OF MIXED GAS

Application filed July 9, 1928, Serial No. 291,336, and in Great Britain November 11, 1927.

According to the U. S. Patent No. 1,587,564, a quantity of the gas obtained by the complete gasification of bituminous fuel, and cooled to the air temperature, is reheated in a regenerator, whence part of the reheated gas passes into the carbonization section of the generator in order to carbonize the fuel in it, and a part passes into a carburetter into which oil is sprayed for the purpose of enriching the gas. The carburetted gas does not return to the regenerator, or to the generator. The regenerator and carburetter are both heated by the gas generated during the air blow period as described, and the waste gases from this period pass out through stack valves in the top of the regenerator and carburetter respectively.

According to the present invention, in order to secure the more effective use of the heat in the air blow gas, the latter instead of passing in parallel through the regenerating and carburetting chambers, passes through these chambers serially, first through the regenerator and next through the carburetter and finally through a preheater. Then on the gas making run a proportion of the gas is tapped off of the discharge main and passed first through the preheater. On leaving the preheater, part of this gas passes through the regenerating chamber to the carbonization chamber, producing gas which is discharged into the main. The remainder of the tapped gas leaving the preheater passes through the carburetting chamber where it is enriched and then after suitable treatment discharged into the main, preferably at a point beyond that at which the gas is tapped off.

The accompanying drawings show diagrammatically in elevation by way of example two different ways of carrying out the invention.

In Figure 1 the carburetter consists of a single vessel as in the above prior patent; in Figure 2 the carburetter is divided into two parts, one being the gas enriching chamber and the other a superheater.

In Figure 1A is a carbonization chamber adapted to receive coal, oil shale, or other bituminous fuel. B is a gasification cham-

ber below the carbonization chamber, into which chamber the carbonized fuel descends. K is a scrubber and L a condenser. R is a valve between the condenser and the main H. U and V are valves for admitting air and steam respectively beneath the chamber B. O is a cooler and P a valve between the cooler and the main. M is a wash box and G is a gas exhauster or pump hereinafter referred to as a circulator. W is a wash-box between the carbonizing chamber A and the scrubber K.

All these parts are arranged as in the plant described in my prior patent above referred to, with the exception of the wash-box W, which, however, forms no part of the present invention.

As in my prior patent, a regenerator D is arranged so that it communicates at the bottom with the chamber B. It also communicates with a carburetter E, but according to the present invention this communication is serial during the air blow period. Also a preheating chamber C is arranged above the chambers D and E. The chamber C communicates with the top of the regenerator through a pipe F and valve I, and with the bottom of the carburetter through a pipe J and valve N.

A circulator G draws gas from the main H as before, and also communicates with the preheating chamber C through a valve Q. The preheating chamber C has a stack valve S. The pipe J is also open to the wash-box M. Oil for enriching the gas is fed to the top of the carburetter at X.

During the air blow period, the valves I, R and Q are closed, and the valve N and the stack valve S opened. The blow gas consequently passes from the chamber B through the chambers D and E in series, the pipe J and the preheating chamber C, and thence is discharged from the plant through the stack valve S. Secondary air is admitted to chamber D through inlet T for burning the air blow gas. During the steam run or water gas period, the valves I, R and Q are opened, and N and S closed, and while carburetting by injecting oil spray at X, the valve P is also open. The gas from the circulator G

chamber D where it divides, part passing downwardly through chamber D, enters the carbonization chamber A, through which it passes, together with the water gas generated 5 from the coke in chamber B to the outlet of washer W, and part through the carburetting chamber E, the wash-box M, the cooler O, the valve P and thence to the main H.

In Figure 2, parts corresponding to those 10 occurring in the previous figure are indicated by the same letters with double dashes. The carburetor E of Figure 1 is here subdivided into a gas enriching chamber E'' and a superheater Y'', the remainder of the apparatus 15 being substantially as in Figure 1. The operation during the air blow and steam run periods, will be understood from the description of Figure 1.

In both arrangements only one stack valve 20 S or S'' is required.

What I claim is:—

1. In apparatus for enriching with oil the gas obtained by the complete gasification of coal, a gasification chamber adapted to contain a fuel bed, means for admitting air and steam respectively into said chamber, a fuel carbonization chamber communicating freely therewith, a gas main in communication 25 with the said carbonization chamber, a regenerating chamber in communication with the gasification chamber, a carburetting chamber communicating with the gasification chamber and also communicating 30 with the main, means for admitting enriching oil to the carburetting chamber, a preheater having means for the escape of waste air blow gas and connections to the regenerator and the carburettor and also to 35 the outlet from the carburettor, means for producing a current of gas during the blow period to pass serially through the regenerating and carburetting and preheating chambers and thence to the atmosphere, and means 40 for recirculating gas drawn from the main during the steam run period through the preheater and carburettor in parallel currents, one current being superheated in the preheater and passed into the fuel carbonization 45 chamber, the other current being carburetted in the carburettor and passed to the gas main at a point beyond the point of withdrawal of recirculation gas from said main. 50

2. In apparatus for enriching with oil the gas obtained by the complete gasification of coal according to claim 1, wherein said means for the escape of gas is a stack valve, and valve means to enable opening and closing of said connections. 55

3. In apparatus for enriching with oil the gas obtained by the complete gasification of coal according to claim 1, including valve means whereby said connections may be opened or closed, valve means to control the 60 flow of gas from the preheater to the carburet- 65

70 rettor and regenerator and to prevent the flow of gas in the reverse directions during the air blow period to admit gas from the outlet of the carburettor to the preheater during the air blow period and to prevent the flow of circulation gas in the reverse direction, said means of the preheater being a stack valve, valves for controlling the admission of air and steam to the generator, and valves for controlling of the recirculation gas 75 and at both outlets for gas to the gas main.

In testimony that I claim the foregoing as my invention I have signed my name this 26th day of June, 1928.
